THREAD-DRAWING MACHINE

Hermann Gunther, Elizabeth, N. J., assignor to
The Singer Manufacturing Company, Elizabeth, N. J., a corporation of New Jersey

Application June 8, 1934, Serial No. 729,625

17 Claims. (Cl. 112—78)

This invention relates to machines for drawing threads in fabrics to be hemstitched. A machine for this purpose commonly comprises a frame which may be constructed with a bed and gooseneck similar to a sewing machine frame and which is fitted with operatively connected upper and lower rotary shafts, fabric feeding mechanism, including a feed-dog, a spring-pressed presser-bar with one or more presser-feet, a throat-plate, a vertically reciprocatory piercer-bar carrying a spear-like piercer blade having fine saw-toothed thread-drawing edges and adapted to penetrate the work and push the longitudinal threads downwardly through a slot in the throat-plate transverse to the line of feed, and a rotary cutter carried by the lower rotary shaft and having a cutting edge transverse to the line of feed for cutting off the drawn threads.

Considerable difficulty has been experienced in adapting machines such as heretofore constructed to the drawing of threads of wide zones of the order of $\frac{1}{4}$ inch, due to the tendency of a piercer blade of this width to push both the transverse and longitudinal threads of the fabric down into the field of action of the cutter, with the result that damaging holes are cut in the work. To avoid this, various expedients have been proposed to laterally spread or tension the fabric so that the transverse threads will be held under strain and prevented from being carried downwardly by the piercer blade. None of the expedients heretofore proposed has proven to be entirely satisfactory for use with wide thread-drawing piercers, or for work from which the threads are to be drawn close to, say $\frac{1}{8}$ of an inch from the edge thereof.

The present invention has for an object to provide a thread-drawing machine with simplified and improved mechanism for spreading or laterally tensioning the work, which mechanism is effective when drawing threads from a relatively wide zone or path in the work or from a zone or path close to the edge of the work.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a vertical longitudinal sectional view of a thread-drawing machine embodying the invention. Fig. 55 2 is a bottom plan view and Fig. 3 is an end ele-

vation of the machine. Fig. 4 is a front elevation, partly in section, of the presser-foot and work-spreading mechanism with the piercer-blade at its highest point. Fig. 5 is a similar view with the piercer blade at its lowest point. Figs. 6 and 7 are sections on the lines 6—6 and 7—7, respectively, Fig. 5. Fig. 8 is a horizontal section through the piercer-blade clamp on the piercer-bar. Fig. 9 is a bottom plan view of the presser-foot. Fig. 10 is a top plan view of the throat-plate and Fig. 11 is a disassembled perspective view of the presser-foot.

The frame of the machine is like the frame of an ordinary sewing machine and comprises a flat bed 1 and standard 2 of an overhanging bracket-arm 3 terminating in the head 4. Journaled in the bracket-arm 3 is the main shaft 5 having at its front end a crank 6 which is connected by the link 7 to the reciprocatory piercer-bar 8 carrying the piercer-blade 9.

The piercer comprises the usual flat spear like head with serrated upwardly divergent edges carried by the cylindrical shank 9' which is clamped against the bottom wall 10, Fig. 8, of a lateral slot 11 in the piercer-bar 8 by means of a clamp-screw 12 carried by a collar 13 surrounding the piercer-bar 8 and fixed to the latter by means of a clamp-screw 14. The collar 13 carries a rearwardly projecting roller-stud 15 which actuates the work-spreading means to be described. It will be observed in Fig. 8 that the slot 11 is wider than the tip end of the piercer clamp-screw 12. This permits of a limited angular or rotary adjustment of the collar 13 on the piercer-bar 8 for a purpose to be described. The piercer-blade may also be adjusted rotatively by loosening the set-screw 12, without disturbing the adjustment of the collar 13 and its roller stud 15 upon the piercer-bar 8.

The main-shaft 5 drives the vertical shaft 16 through the one-to-one bevel gears 17 and the vertical shaft 16 drives the lower rotary shaft 18 through the one-to-one bevel gears 19. The lower rotary shaft 18 carries the usual rotary cutter blade 20 having an inclined sharpened cutting edge 21 which shears off the drawn threads in cooperation with the forward lower edge 22 of the piercer-slot 23 in the throat-plate 24.

The throat-plate 24 is also provided with the usual lateral feed-dog clearance slots 25, 25 for the lateral feed-dog sections 26, 26 and with the front and back central feed-dog clearance slots 27, 27 for the central feed-dog sections 28, 28. The feed-dog sections 26 and 28 are integrally related and carried as usual by the feed-bar 29, Fig. 55

3, fulcrumed on the usual feed-rocker arms 30 of the feed rock-shaft 31 fulcrumed below the bed 1 on the usual trunnion screws 32. Rising and falling movements are imparted to the feed-bar 5 by the roller 33 on the arm 34 of the feed-lift rock-shaft 35 fulcrumed on the trunnion screws 36. The usual feed-actuating pitmen 37, 38 extend upwardly from the feed rock-shafts 35 and 31 to the feed-actuating eccentrics 39, 40 on the 10 main-shaft 5.

There is mounted in the head 4 the usual spring-pressed presser-bar 41 to which is detachably secured by means of a screw 42 the presser-foot shank 43 in the lower end of which is horizontally journaled the bearing stud 44 fixedly secured to the carrier 45 which has two laterally spaced and forwardly extending arms 46, 46 carrying the horizontal pivot-screws 47, 47 for the sole-piece 48, which is thus free to tilt universally 15 relative to the shank 43.

The carrier arms 46 of the presser-foot have vertical ways 49 formed therein to receive the vertical positioning ribs 50 of the independently vertically adjustable extension-plates 51 held in 20 adjusted position by screws 52 which pass through oversize clearance holes 53 in the respective extension-plates 51.

Pivottally attached to the upper ends of the vertical extension-plates 51 by screws 54 are the 30 depending fingers 55 formed at their lower ends with forwardly extending work-engaging extremities 56 having slightly roughened lower work-engaging faces 57, Fig. 9, adapted to engage the work exposed by the rectangular aperture 58 in the presser-foot sole-plate 48. The plates 51 are adjusted on the carrier arms 46 so that the work-engaging faces 57 of the work-spreading fingers 55 project slightly and sufficiently below the level of the lower face of the 35 presser-foot sole-plate 48 to engage and spread the work.

The fingers 55 are biased inwardly into engagement with the stop-pin 59 by means of the springs 60 which are supported by the screws 61. The 40 lower horizontal extremities 56 of the fingers are formed with clearance notches 62 for the piercer-blade 9.

It will be observed in Fig. 4 that when the fingers are in engagement with the stop-pin 59, 50 the inner edges of the fingers diverge upwardly at opposite sides of the roller stud 15 on the piercer-bar. As the piercer descends the feed-dog drops below the throat-plate. The presser-foot and work-spreading fingers 55 press the work upon 55 the throat-plate with the fingers 55 in their inner positions. Just before the point of the piercer reaches the fabric the roller stud 15 simultaneously engages the inner edges of the fingers 55 and initiates the work-spreading movement which 60 continues until the piercer reaches its lowest point, Fig. 5; the fingers 55 slipping over the fabric but having sufficient grip thereon to laterally spread or tension the fabric so that the cross-threads thereof will not be carried down by the 65 piercer-blade. Moreover, it will be observed that the arcs of motion of the work-engaging extremities of the fingers 55 about their respective pivots 54 are outwardly and downwardly, thus increasing the grip or drag of the fingers 55 upon 70 the work as their spread increases. In the fully spread positions of the fingers 55 their work-engaging faces are substantially or so nearly vertically below their respective pivots that they remain in their spread positions and hold the fabric 75 and cross-threads under lateral tension as the

piercer rises and until its point is clear of the work and the rotary knife has passed its cutting position and severed the drawn longitudinal threads. The feed-dog then rises and lifts the fabric and presser-foot from the throat-plate, whereupon the springs 60 return the fingers to their inner positions against the stop-pin 59.

Because of the continuous spreading action of the fingers 55 during the descent of the piercer through the fabric, it is possible to use piercer-blades of considerable width, say $\frac{1}{4}$ inch, without damage to the fabric. Furthermore, by applying the spreading fingers to the fabric close to the piercer, and by using center feed-dog sections as well as the side feed-dog sections it is 15 possible to draw threads as close as may be desired to the edge of the fabric.

The roller-stud 15 may be lubricated by means of an oil-saturated felt wick 15', Fig. 3, which may be suitably supported in position to be engaged by the roller-stud 15 as the latter ends 20 its up-stroke.

The collar 13 should be so adjusted or set on the piercer-bar 8 that the roller-stud 15 will act simultaneously and equally on the spreading 25 fingers 55.

The invention is not to be understood as limited to the specific forms and arrangements of parts shown and described as such forms and arrangements are merely illustrative of one embodiment 30 of the invention from which the principles of the invention will be readily understood and may obviously be embodied in a variety of forms by those skilled in the art.

Having thus set forth the nature of the invention, what I claim herein is:—

1. In a thread-drawing machine, the combination with a piercer-blade, a reciprocatory piercer-bar carrying said blade, a feed-dog, and a presser-foot, of means actuated by said piercer-bar to spread the work laterally of the line of feed.

2. In a thread-drawing machine, the combination with a piercer-blade, a reciprocatory piercer-bar carrying said blade, a feed-dog, and a presser-foot, of separable means actuated simultaneously in opposite directions by said piercer-bar to spread the work laterally of the line of feed.

3. In a thread-drawing machine, the combination with a piercer-blade, a reciprocatory piercer-bar carrying said blade, a feed-dog, and a presser-foot, of means movable laterally of the line of feed and actuated by said piercer-bar on the down-stroke of the latter to spread the work.

4. In a thread-drawing machine, the combination with a piercer-blade, a reciprocatory piercer-bar carrying said blade, a feed-dog, and a presser-foot, of work-spreading means mounted on and movable relative to said presser-foot laterally of the line of feed.

5. In a thread-drawing machine, the combination with a presser-foot having an aperture and universally tiltable sole-plate, of work-spreading fingers pivotally carried by the presser-foot and having work-engaging extremities disposed in the aperture in said sole-plate.

6. In a thread-drawing machine, the combination with a presser-foot having an apertured and universally tiltable sole-plate, of work-spreading fingers pivotally carried by the presser-foot and having work-engaging extremities disposed in the aperture in said sole-plate, means for simultaneously moving said fingers away from one another to spread the work, and spring means for imparting recovery movements to said fingers.

7. In a thread-drawing machine, a presser-foot having an apertured sole-plate, and a pair of depending work-spreading fingers pivotally mounted at their upper ends on said presser-foot and adapted to engage the work exposed within the aperture in said sole-plate. 5
8. A presser-foot for thread-drawing machines comprising a shank, a carrier pivoted to said shank, a sole-plate pivoted to said carrier, and 10 a pair of work-spreading elements pivotally mounted on said carrier independently of said sole-plate. 10
9. A presser-foot for thread-drawing machines comprising a shank, a carrier pivoted to said shank, a sole-plate pivoted to said carrier, and 15 a pair of work-spreading elements pivotally mounted on said carrier independently of said sole-plate, said work-spreading elements being independently vertically adjustable. 15
10. In a thread-drawing machine, a reciprocatory piercer-bar, a piercer-blade carried thereby, a feed-dog, a presser-foot having a sole-plate, a 20 pair of pivoted and depending work-spreading fingers, and a stud carried by said piercer-bar in position to engage and spread said fingers on the down-stroke of said bar. 20
11. In a thread-drawing machine, a presser-foot, a vertical spring-pressed presser-bar, a 25 throat-plate, a feed-dog, a pair of depending work-spreading fingers pivoted at their upper ends to said presser-foot and having roughened work-engaging surfaces at their lower ends, a reciprocatory piercer-bar, a piercer carried thereby, and means for spreading said fingers on the 30 down-stroke of said piercer-bar. 30
12. In a thread-drawing machine, a presser-foot, a vertical spring-pressed presser-bar, a 35 throat-plate, a feed-dog, a pair of depending work-spreading fingers pivoted at their upper ends to said presser-foot and having roughened 40
- work-engaging surfaces at their lower ends, a reciprocatory piercer-bar, a piercer carried thereby, and means for spreading said fingers on the down-stroke of said piercer-bar, the work-engaging surfaces of said fingers being substantially vertically below their respective pivotal axes in the spread position of said fingers. 5
13. A thread-drawing machine having a reciprocatory spear-like piercer, a cutter, a feed-dog, a presser-foot, and work-engaging means moving laterally of the line of feed during the descent of the piercer through the work for spreading the work. 10
14. A thread-drawing machine having a reciprocatory spear-like piercer, a cutter, a feed-dog, 15 a presser-foot, and laterally and downwardly movable pivoted means carried by said presser-foot for exerting a continuously increasing spreading grip upon the fabric as the piercer descends through the latter. 15
15. A thread-drawing machine having a reciprocatory spear-like piercer, a cutter, a feed-dog, 20 a presser-foot having an aperture therein through which the piercer operates, and laterally movable fabric-spreading means for engaging the work in said aperture closely adjacent said piercer. 25
16. In a thread-drawing machine, a reciprocatory piercer, a complementary cutter, fabric feeding mechanism, a pair of fabric spreading elements initially in engagement with the fabric in the path of the piercer, and means for spreading said elements as the piercer descends. 30
17. In a thread-drawing machine, a reciprocatory piercer, a complementary cutter, fabric feeding mechanism, a pair of fabric spreading elements, and means for moving said elements simultaneously in opposite directions as the piercer descends. 35

HERMANN GUNTHER. 40
